UNITED STATES PATENT OFFICE.

JAMES HARRY LEMMON, OF MILLTOWN, INDIANA, ASSIGNOR TO LOUISVILLE CEMENT COMPANY, OF LOUISVILLE, KENTUCKY, A CORPORATION OF KENTUCKY.

KILN.

1,401,481.

Specification of Letters Patent. Patented Dec. 27, 1921.

Application filed March 13, 1919. Serial No. 282,503.

To all whom it may concern:

Be it known that I, JAMES HARRY LEMMON, a citizen of the United States, residing at Milltown, in the county of Crawford and State of Indiana, have invented certain new and useful Improvements in Kilns, of which the following is a specification, reference being had therein to the accompanying drawing.

10 This invention relates to kilns, and while susceptible to a variety of uses, is more particularly adapted for the burning of lime, cement and similar materials.

In lime and cement kilns, it has not heretofore been the general practice to employ a bridge wall, or partition, dividing the kiln into opposed chambers, because the bridge wall, under the action of the high heat involved, is subject to expansion and contraction, and being built up in connection with, and as a part of, the outer wall of the kiln, has had a tendency to buckle or collapse, and also a tendency to injuriously affect the outer wall of the kiln proper, to which the bridge wall was connected and of which it was an integral part.

It is one of the primary objects of the present invention, therefore, to overcome existing objections in kilns, as heretofore constructed, to increase the life of the kiln, without substantial increase in cost of production, and with a decrease in cost of maintenance, and to provide a more thorough and uniform calcination of the material passing through the kiln.

It is obvious, of course, that the improvements herein contemplated are readily applicable to kilns of various designs and constructions, and while illustrated in connection with a stationary kiln, it is possible to secure advantageous results in connection with a rotary kiln.

In carrying out the invention, it is proposed to provide in operative association with a surrounding wall for the kiln, a longitudinally disposed bridge wall, or partition, to divide the kiln into opposed chambers, the said bridge wall or partition being constructed and arranged whereby to allow for the relative expansion and contraction between the bridge wall and the surrounding wall of the kiln, without injuriously affecting either of the said parts. More particularly, this feature of the invention resides in the provision of a bridge wall built up

entirely independently of the side walls of the kiln proper, and spaced from said walls of the kiln at both its sides and edges, whereby to permit the bridge wall to expand to a considerable extent under the action of the 60 heat.

Again, the invention includes a novel construction of kiln wall and operatively associated bridge wall, the kiln wall being provided at opposite sides with alined recesses adapted to receive the edges of the bridge wall, the walls surrounding said recesses being spaced from opposite surfaces and edges of the bridge wall, and in the preferred embodiment of the invention, the 65 outer walls of the kiln being relatively thickened at said recessed parts.

The invention further includes means whereby the fuel supply, such as gas or oil, may be introduced into the chambers of the 70 kiln formed by said bridge wall or partition, at points removed from the surrounding wall of the kiln to the end that such gas or oil, or other fuel, will be projected to a large extent into the central zone of the kiln 75 to provide for a more uniform distribution of fuel among the mass of material to be calcined, the tendency of flames and gases in previous construction, where the fuel supply is introduced only around the inner wall of 80 the kiln, being to flow upward as soon as released in the interior of the kiln without reaching the mass of material in the central zone, thereby creating a variable condition 85 of calcination; and in carrying out this feature of the invention it is proposed to introduce the fuel, such as gas or oil through the ends of the bridge wall, the said flues connecting with laterally disposed outlets or ports in said bridge wall in direct contact 90 with the mass of stone, etc., positioned in the chambers of the kiln to be burnt.

It is further contemplated by the invention to provide a kiln of simple, novel and inexpensive construction, strong and durable, and highly efficient and satisfactory in use.

Still further improvements and novel details in the construction and arrangement of parts will be appreciated by those skilled 105 in the art from the description to follow, when considered in connection with the accompanying drawings, which form a part thereof, and wherein is disclosed, for the purpose of illustration, a convenient and 110

satisfactory embodiment of the invention, though it is to be borne in mind in this connection, that many minor changes in details and arrangements of parts may be resorted to without departing from the spirit of the invention.

In the drawings—

Figure 1 is a vertical view, partly in section, of a kiln, with my improvements applied, parts being broken away.

Fig. 2 is a top plan, parts being illustrated in broken lines; and

Fig. 3 is a vertical section substantially on the line 3—3 of Fig. 2.

15 With more particular reference to the drawings, 1 is the outer surface and 2 the inner surface of the surrounding wall or lining for the kiln, the said lining being constructed of any suitable material for the 20 purpose, such as fire brick, and taking a substantially cylindrical form. Since the top and bottom portions of the kiln, including the means of feed and discharge, etc., constitute no part of the present invention, and 25 may take the form of any of the approved types, it is not necessary to illustrate or describe them herein.

The surrounding wall of the kiln is conveniently widened or thickened at 3, the said 30 widened portions being cut out whereby to provide opposed recesses 4 for the reception of a longitudinally disposed bridge wall or partition 5.

The bridge wall 5 is conveniently constructed of any suitable material for the 35 purpose, the opposite sides of the bridge wall conveniently being tapered inwardly as at 6 adjacent the upper edge thereof.

The bridge wall is of a thickness slightly 40 less than the width of the recesses 4, whereby to leave a clearance space of sufficient area between opposite surface of the bridge wall and the side walls of the recess 4 in the lining. Opposite edges of the brick wall are

45 conveniently curved, as at 7 to correspond to the general curvature of the outer surface or lining 1 of the kiln, but said bridge wall is of a length slightly less than the diameter of the wall of the kiln represented by the 50 outer surface thereof, whereby to leave a free clearance space between said outer surface or lining of the kiln, and the edges of the bridge wall. From the construction thus far described, it will be observed that that 55 portion of the bridge wall positioned within the recesses formed by the kiln walls, will be entirely independent and free of the surrounding wall of said recesses whereby to allow for all necessary expansion in the normal use of the kiln.

Advantage is taken of the bridge wall to deliver a part of the gas or fuel directly into the chambers of the kiln formed by said bridge wall, and with this in view, opposed 65 conduits or flues 7 leading from any suitable

source of supply, such as a gas producer, not illustrated, project through the outer lining of the kiln, thence through the edges of the bridge wall to a point beyond the inner surface of the kiln wall, where said flues 70 communicate with laterally disposed passages 8 projecting through the bridge wall for communication with the chambers formed by said bridge wall and the surrounding kiln wall.

75 It will be understood, of course, that other flues may be provided in the surrounding wall or lining of the kiln proper.

It is believed the operation and use of the kiln as above described, will be obvious. 80 Since the bridge wall is built entirely independent of the wall of the kiln, the expansion and contraction of the bridge wall, incident to the high heat of the kiln, is taken care of without affecting the walls of the 85 kiln or buckling or otherwise injuring the bridge wall itself. The wall of the kiln is reinforced at the recesses provided for the accommodation of the bridge wall by the thickened mass of material constituting the 90 lining, and the gas or fuel supply is more properly distributed throughout the entire body of the kiln, by the introduction of the fuel, through the flues or conduits in the bridge wall.

95 What I claim is:

1. In a kiln of the character described, the combination of an outer wall and a bridge wall separate therefrom, the sides and ends of said bridge wall being spaced 100 from the outer wall to allow free expansion and contraction thereof.

2. In a kiln of the character described, the combination of an outer wall having opposed recesses, and an interior bridge wall, 105 along the kiln positioned within said recesses and spaced from the walls thereof, substantially as and for the purpose described.

3. In a kiln of the character described, 110 the combination of an outer wall, having associated means forming opposed receiving channels, and a bridge wall with opposite sides thereof disposed within said channels and spaced from contact with the walls 115 thereof.

4. In a kiln, the combination of a wall having opposed thickened portions with longitudinally extending recesses, and a longitudinally disposed bridge wall positioned at its sides in said recesses and spaced from the walls surrounding said recesses.

5. In a kiln, the combination of an outer wall, a suitably supported interior bridge wall; said bridge wall extending substantially from side to side of the outer wall, but spaced therefrom to allow for expansion and gas supply flues communicating with the kiln chambers through said bridge wall.

6. In a kiln, the combination of an outer wall, of a partition or bridge wall having openings projecting laterally therethrough, and communicating openings projecting 5 through opposite edges of the bridge wall for the reception of a flue or the like, and the inner surface of the outer wall of the kiln being inwardly curved to a point adjacent said transverse openings of the bridge 10 wall.

7. In a kiln, the combination of an outer wall having opposed recesses, and an inte-

rior bridge wall having its ends received in the opposed recesses, the ends of the bridge wall being normally spaced from 15 the outer face of the outer wall and its sides normally spaced from the walls of the recesses to allow for expansion.

In testimony whereof I hereunto affix my signature in the presence of two witnesses. 20

JAMES HARRY LEMMON.
